UNITED STATES PATENT OFFICE

131,480

DESIGN FOR A SET OF GAME PIECES

Joseph W. Patterson, Tulsa, Okla.

Application December 5, 1941, Serial No. 104,499

Term of patent 14 years

To all whom it may concern:

Be it known that I, Joseph W. Patterson, a citizen of the United States of America, residing at Tulsa, in the county of Tulsa and State of Oklahoma, have invented a new, original, and ornamental Design for a Set of Game Pieces, of which the following is a specification, reference being had to the accompanying drawing, forming part thereof.

Figure 1 is a top plan view of a set of game pieces, showing my new design, and

Figure 2 is an enlarged isometric view of one of the playing pieces thereof.

The backs of the respective game pieces are conventional.

I claim:

The ornamental design for a set of game pieces, as shown and described.

JOSEPH W. PATTERSON.
